UNITED STATES PATENT OFFICE.

SAMUEL KELLETT, OF SAN FRANCISCO, CALIFORNIA.

DESIGN FOR CENTER-PIECE IN ALTO-RELIEVO.

Specification forming part of Design No. 6,000, dated July 16, 1872.

SPECIFICATION.

To all whom it may concern:

Be it known that I, SAMUEL KELLETT, of San Francisco, in the county of San Francisco and State of California, have invented and produced a new and original Design for Center-Piece in Alto-Relievo; and do hereby declare that the following is a full and exact description of the same, reference being had to the accompanying drawing and to the letters of reference marked thereon.

My new design consists of a rosette, A, from which radial arms B extend to near a lozenge-molding C. Between this molding and an outer beaded molding, D, are placed bouquets of flowers and leaves E, and alternate bunches

of fruit and leaves F, connected by stalks or withes, the whole being surrounded by shell-work G.

Having thus described my invention, what I claim, and desire to secure by Letters Patent, is—

1. The radial arms B, moldings C and D, shell-work G, substantially as shown.
2. The ornaments F and E, separate or in combination, set forth and shown.

In witness whereof I have hereunto set my hand and seal.

SAML. KELLETT. [L. S.]
